UNITED STATES PATENT OFFICE.

EDWIN FRANCIS CREAGER, OF LANCASTER, PENNSYLVANIA.

DESIGN FOR A BALL RETAINER AND SEPARATOR.

SPECIFICATION forming part of Design No. 30,183, dated February 14, 1899.

Application filed January 23, 1899. Serial No. 703,188. Term of patent 14 years.

To all whom it may concern:

Be it known that I, EDWIN FRANCIS CREAGER, a citizen of the United States, residing at Lancaster, in the county of Lancaster and 5 State of Pennsylvania, have invented and produced a new and original Design for Ball Retainers and Separators; and I do hereby declare the following to be a full, clear, and exact description of the invention, such as 10 will enable others skilled in the art to which it appertains to make and use the same.

The design herein illustrated is for a retainer or separator to hold and separate a 15 number of balls—such, for example, as one commonly employed in bicycle-bearings.

The distinguishing feature of the design is the form, which is substantially that of a cylindrical ring or tubular annulus minus a 20 small interior segment, which is cut away by different meridians or by an oblique plane, so that, as shown, the opening formed by removing the segment is defined by circles of 25 different diameters. The ring thus incloses an axial space of less diameter at the bottom than at the top in the relation shown. A se-

ries of perforations lie in the outer curve of the ring. If extended upon a plane, each perforation would be substantially elliptical in outline or circumference.

In the drawings, Figure 1 is a bottom plan 30 view with reference to Fig. 3. Fig. 2 is a top plan view, and Fig. 3 is a section taken on the line 3 3 of Fig. 2.

1 indicates the ring; 2, the bottom axial space within the ring; 3, the perforations; 4, 35 the lower circle, and 5 the upper circle, defining the opening caused by the lack of the small segment.

I have indicated, as an example, five perforations. 40

What I claim is—

The design for a ball retainer or separator substantially as shown and described.

In testimony whereof I affix my signature in presence of two witnesses.

EDWIN FRANCIS CREAGER.
